UNITED STATES PATENT OFFICE.

FREDERICK VAN DEN BOSCH, OF PARKER'S LANDING, PENNSYLVANIA.

CUTTING MECHANISM FOR HARVESTERS.

SPECIFICATION forming part of Letters Patent No. 357,512, dated February 8, 1887.

Application filed December 23, 1885. Serial No. 186,525. (No model.)

To all whom it may concern:

Be it known that I, FREDERICK VAN DEN BOSCH, a subject of the King of Netherlands, and a resident of Parker's Landing, in the county 5 of Armstrong and State of Pennsylvania, have invented certain new and useful Improvements in Cutting Mechanism for Harvesters; and I do hereby declare that the following is a full, clear, and exact description of the invention, 10 which will enable others skilled in the art to which it appertains to make and use the same, reference being had to the accompanying drawings, which form a part of this specification, and in which—

15 Figure 1 is a plan view of a portion of the cutting mechanism of a harvester provided with my improved cutter-bar. Fig. 2 is a similar view showing the keeper removed and one of the blades removed, and Fig. 3 is a 20 view of one of the blades.

Similar letters of reference indicate corresponding parts in all the figures.

My invention has relation to that class of cutter-bars in which the blades may be removed by removing a keeper at the end of the 25 bar and sliding the blades to one side, the blades having slots or notches in their side edges fitting upon studs upon the cutter-bar; and it consists in the improved construction 30 and combination of parts of the same, as hereinafter more fully described and claimed.

In the accompanying drawings, the letter A indicates the finger-bar, having the fingers B, which are of the usual construction; and 35 C is the cutter-bar. This cutter-bar is provided with a number of equidistant studs, D, having suitable flat heads, E, which will project over the upper sides of the blades F. One of the rear corners of these blades is provided with a recess or notch, G, near the rear edge. The portion of the blade between the notch and said edge is cut off near the base 40 of the notch, so as to form a short inclined outer edge, H, parallel with the forwardly-inclined edge of the blade upon that side. The other rear corner is cut away so as to leave two inclined edges, I and J, having a 45 step, P, between them, each of said two faces or edges being parallel with the edge H.

50 It will be seen that when the blades are

placed upon the cutter-bar, with the notches fitting upon the studs of the cutter-bar, the opposite edges of the blades will fit into each other and retain each other in position; and at one end of the cutter-bar is secured a keeper, 55 K, having a slot, L, and inclined edges L' and M, which correspond to and fit against the zigzag-shaped edge of the adjoining blade, fitting upon the outermost stud, and this keeper is retained in place by means of a screw, N, 60 passing through a perforation, O, in the keeper and into the cutter-bar. It will thus be seen that one blade will secure the other fitting with its zigzag-shaped edge against the zigzag-shaped and slotted edge, and the keeper will 65 secure the outermost blade, and when this keeper is removed the blades may be removed successively, either for the purpose of grinding them or for the purpose of replacing a broken blade, or for any other purpose.

70 It is impossible for any of the blades to become loose or to drop out, as the notched edge is retained by the stud, and the overhanging portion of this edge, forming the outer edge of the stud, will retain the zigzag-shaped ad- 75 joining edge.

I am aware that sickle-bars have been made with detachable cutters which were retained upon the cutter-bar by means of studs engaging notches or slots in the blades, and I do 80 not wish to make any broad claim for such construction; but I am not aware that the blades have been formed with correspondingly cut-out edges of zigzag shape and formed with notches fitting upon studs, one keeper at one 85 end of the bar securing all the blades; and

I therefore claim and desire to secure by Letters Patent of the United States—

In the cutting mechanism for harvesters, the combination of a cutter-bar having a number 90 of equidistant flat-headed studs, blades secured thereto, each of said blades having a notch or recess at one corner near the rear edge, and having the portion between said notch and the rear edge cut away to near the 95 base of said recess, said cut-away portion having an inclined edge, the other corner of said blades being cut away so as to leave two inclined edges having a step between them, each 100 of said inclined faces or edges being parallel

with the forwardly-inclined edge of the blade upon the side in which the said notch is located, a keeper having one end provided with a hole and the other with a recess or notch 5 and two inclined faces or edges, and a screw for securing said keeper to the cutter-bar.

In testimony that I claim the foregoing as

my own I have hereunto affixed my signature in presence of two witnesses.

FREDERICK VAN DEN BOSCH.
